BLOWTORCH AND ATTACHMENTS

Carl C. Boyd, Rock Island, Ill.

Application July 10, 1935, Serial No. 30,631

4 Claims. (Cl. 158—33)

The present invention relates to improvements in blowtorches and in attachments for use therewith. Among the objects of this invention are to provide a blowtorch which is improved in various ways over heretofore existing structures of this type; to provide a torch to which can be applied several attachments; to provide improved attachments of various sorts which can be applied to a blowtorch to adapt it for various uses; and such further objects, advantages, and capabilities as will hereafter appear and as are inherent in the construction disclosed herein. My invention further resides in the combination, construction, and arrangement of parts illustrated in the accompanying drawings and, while I have shown therein preferred embodiments of the various parts of this invention, I desire the same to be understood as illustrative only and not to be interpreted in a limiting sense.

20 In the drawings annexed hereto and forming a part hereof,

Fig. 1 is a plan view and Fig. 2 an elevation of my improved torch;

Fig. 3 represents an end elevation as viewed 25 from the left end of Fig. 2, as indicated by the arrows and line 3—3 in that figure;

Fig. 4 represents a longitudinal section of the structure shown in Figs. 1 and 2;

Fig. 5 represents a transverse section taken 30 substantially along the plane indicated by the line 5—5, Fig. 4;

Fig. 6 represents a transverse section taken substantially along the plane indicated by the line 6—6, Fig. 4;

35 Figs. 7, 8, and 9 represent in elevation various shapes of soldering tips as applied to the mouth of the blowtorch;

Fig. 10 represents a transverse section taken substantially along the plane indicated by the 40 line 10—10, Fig. 9;

Fig. 11 represents a melting bowl applied to the mouth of the torch;

Fig. 12 represents a longitudinal section taken substantially along the plane indicated by the 45 line 12—12, Fig. 11;

Fig. 13 represents a plan view of a stove attachment to be applied to the mouth of the torch;

Fig. 14 represents a longitudinal section taken 50 substantially along the plane indicated by the line 14—14, Fig. 13;

Figs. 15, 16, and 17 represent, respectively, a side elevation, a plan view, and an end elevation of a paint-burning attachment to be applied to 55 the mouth of the blowtorch, Fig. 17 being taken

from the left in Fig. 16, as indicated by the arrows and line 17—17, Fig. 16.

Fig. 18 represents an end view, detached, of the hood shown in Figs. 1, 2, and 4 as encasing the head of the blowtorch.

Reference will now be made in greater detail to the annexed drawings for a more complete description of this invention. The blowtorch proper comprises, essentially, a body 1, head 2, neck 3, and feet 4. The body 1 is provided with 10 a hook 5 whereby the torch may be suspended as, for example, when being used by a telephone lineman working in an elevated position, such as on a pole. A pump 6 extends into an end of the body 1 and comprises among its parts a cap 7 which the barrel of the pump has screw-threaded connection. This cap 7 has screw-threaded connection with the cap 8 of the torch body 1, a gasket 9 being inserted between the two caps 7 and 8 to prevent leakage at this joint. The cap 20 15 8 may be either screw-threaded to the cylinder of the body of the torch or connected thereto permanently by brazing or soldering. The cap 8 is preferably flattened at one point, as indicated in Figs. 1, 2, and 4, to have an opening formed 25 therein for the reception of the plug 10, between which and the cap 8 is a gasket 9a. This opening constitutes the filling opening whereby the fuel is put into the body of the torch.

Within the cylinder of the pump 6 is a pump 30 rod 11 which is enlarged at its outer end and screw-threaded, as indicated at 12, so that it may be screwed into corresponding threads in the cap 7. This enlarged portion seats against the bottom of the hole in the cap so as to prevent 35 leakage around the pump rod. A knob 13 is provided which serves as a handle for operating the pump rod and for turning this to cause seating of the threaded portion against the bottom of the hole, and the reverse. A piston 14 of any 40 approved construction may be attached to the inner end of the pump rod and serves to force air into the interior of the blowtorch. A spring-pressed valve member 15 seats in a depression in the end of the pump and also serves to prevent 45 escape of gasoline or air from the interior of the torch. A plug 16 is provided with an opening for the reception of the spring 17, as is evident from Fig. 4.

An automatic valve body 19 has a ball valve 20 50 55 therein for controlling the flow of fuel therethrough. When the head of the torch is turned upwardly, the fuel will run to the end of the body in which the pump is located and the ball 20 will roll to the corresponding end of the open-

ing 21. This permits the gasoline to flow through the pipe 22 into the chamber 21, and from thence through the pipe 23 to the wicking 24 in the neck 3. From here it flows out through the channels 5 leading to the nozzle 25 where it vaporizes and burns, the flame shooting out of the mouth 26 in the common way. The pipe 23 and neck 3 are connected to a cap 23a which may be soldered, brazed, or connected by screw-threading to the body 4, but it is now considered preferable to unite these parts by solder when they are made of metal. The chamber 21 is sufficiently inclined so that when the head end of the torch is raised and is resting on the feet 4 the ball will roll to the forward end of the chamber 21. On the other hand, when the torch is turned with its head up, the ball will roll to the opposite end of the chamber 21, permitting the fuel to be drawn through the pipe 22 from the lower end of the body. When the torch is directed downwardly, the fuel is drawn through the pipe 27 and feeds through the chamber 21 and pipe 23 to the wicking 24. A valve 28 is controlled by a handle 29 and is used to regulate the flow of fuel to the nozzle 25 so as to regulate the flame produced by the torch. The handle 29 is made of a material which is to a certain degree heat non-conducting, so that it will be possible to regulate the valve at any time without getting burned, even though the torch may have been operating for some time.

A hood 30 encloses the top and sides of the head 2 and is held to the head by means of the screws 31. Bosses on the inside of the hood 35 space the same from the head, leaving an air space between the two to reduce heat radiation from the head to the hood. This also leaves an air space through which the air can enter to reach the slot 32 and the openings 33 to furnish the air needed for combustion of the fuel. As shown in Fig. 4 the feet 4 are connected by a cross member 34, thus helping to make a rigid construction for the support of the forward end of the torch to prevent burning of whatever the torch may be laid upon. A screw 35 serves as means whereby attachments may be fastened to the torch.

A pre-heating pan is shown at 36 and, as shown in Fig. 6, the walls of this pan rise along the sides of the head to insure that the flames from the burning pre-heating fluid will cause proper heating of the head so that the fuel issuing from the nozzle 25 will be in proper condition for combustion. The feet 4 are shown in Figs. 5 and 6 as being pivotally connected to the pre-heating pan at 37. As shown in dotted lines in Fig. 2, these can be turned back out of the way under the head 2.

As shown in Figs. 7, 8, and 9, various types of soldering coppers can be attached to the head 2. The tip or copper 38 is of the short, heavy variety, common to heavy duty irons but, as shown in dotted lines, its base is hollow for access of the heating flame. Also, the tip is provided with a 65 tubular projection 39 which fits in the mouth 26 of the torch and is fastened therein by means of the screw 35. Openings 40 extend from the hollow in the base of the tip to the surface thereof to permit escape of the products of combustion 70 and also enable the flame to reach into the tip and not be held back by stagnant air therein. A cross section through the openings 40 would be similar to the cross section shown in Fig. 10.

Adaptors 41 and 42 are provided for the tips 75 43 and 44, the principal difference between these

adaptors being the size of opening provided for the reception of the tips. Of course, if desired, the tips 43 and 44 could be made integral with the adaptors 41 and 42 so that these coppers would be identical with that shown in Fig. 7 except for the size and shape of the tips. It is unnecessary to specify the uses of these various tips as they are well known to persons skilled in the art.

Reference will now be made to the attachments shown in Figs. 11 to 18, inclusive. The attachment shown in Figs. 11 and 12 is a melting pot, such, for example, as a Babbitt ladle. This comprises a bowl 46 provided with pouring spouts 47 and a hollow attaching neck 48. The attaching neck is slotted, as shown at 49 for the reception of the screw 35 and is continued forwardly under the bowl 46 in the form of a wall 50, forming with the bottom of the bowl a heating chamber 51.

Figs. 13 and 14 illustrate a small stove which may be attached to the mouth of the blowtorch for the heating of water, making of coffee, frying, or any other purpose for which such an article might be used. This stove is provided with a 25 neck 52 which surrounds the mouth 26 whereby to support the stove body on the torch. The weight of the stove and the article supported thereby will be, as shown by Fig. 2, nearly over the feet 4, and the weight of the body of the torch 30 will therefore tend to hold the torch and supported body in the intended position. Grooves 53, between the narrow ribs 54, furnish exits for the products of combustion passing into the stove body from the torch. A central supporting body 55 has a hole 56 therethrough for the passage of the flame and products of combustion, this body being supported from the rim 58 by ribs 57. A deflector 59 is located within the cavity in the body of the stove and tends to throw the flame 40 upwardly, causing a better distribution of the heat to all parts of the stove top.

A paint-burning nozzle is illustrated in Figs. 15, 16, and 17, and is shown as having a neck 60 comparable to 48 in Fig. 12 and 52 in Fig. 14. 45 This is slotted for the reception of the screw 35 in the same manner as illustrated in Fig. 11. The mouth 61 is narrow in one direction and wide flaring at a right angle thereto, as is obvious from Figs. 15 and 16. Holes 62 permit the access 50 of air to facilitate combustion. The shape of this nozzle will result in a wide spread flame for the burning off of a wider strip of paint than usual in the use of a blowtorch for this purpose.

It will of course be understood that the specific 65 description of structure set forth above may be departed from without departing from the spirit of my invention as set forth in this specification and the appended claims.

Having now described my invention, I claim: 60
 1. A blowtorch for operation either end up, horizontally, or any intermediate position, comprising an elongated body and a head arranged with their longitudinal axes substantially parallel so that the flame of the torch will be projected in the direction of the length of the body, said body having a valve therein whose discharge end is connected to the nozzle of the head, pipes connected to the valve and leading to opposite end portions of the body to draw fuel from the body 70 and supply it to the valve, and said valve including automatically functioning means to close the discharge from one or the other of said pipes, depending upon the position of the torch with relation to a horizontal plane, the pipes being 75

connected one to each end of the valve and each pipe extending toward the opposite end of said body and into proximity thereto.

2. A blowtorch comprising a tubular body having a pump extending through one end thereof longitudinally of the body, a head directed forwardly away from the opposite end of the body, tubular means connecting the interior of the head with the interior of the body, a hollow valve body located within the blowtorch body and having an exit opening connected to said tubular member to carry liquid fuel thereto, said valve body having within its interior a rolling ball valve member, said valve body having a pair of openings leading from opposite ends of its interior opening, and tubular members connected with said openings and extending past the valve body and into proximity to the opposite ends of the torch body, the ball serving to close one end of the body opening or the other, in accordance with which end of the valve body opening is lower.

3. A structure as defined by claim 2 in which the valve body is mounted with its longitudinal axis making an acute angle with the axis of the

torch body, the vertex of the acute angle pointing in a direction away from the burner of the torch.

4. A blowtorch comprising a tubular body having a pump extending through one end thereof in the direction of the length of the body, a tubular neck extending from the opposite end of the torch body in the direction of the length of the body, a head carried by the neck and provided with an opening communicating with the interior thereof, said head having a nozzle positioned to direct a jet in the direction of the length of the torch and the opening in the head connecting the nozzle with the interior of the neck, and an automatically functioning valve within the body to insure proper flow of fuel to the neck as the inclination of the torch is changed, said valve having tubular openings therein and a ball in operative relation to said openings to control the flow of fuel through the valve, and the tubular openings having tubes connected to the ends thereof and each extending to the end of the body opposite to that end of the valve to which the tube is connected.

CARL C. BOYD.
